(57) **CLAIM**

The ornamental design for an artificial lash extension, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of an artificial lash extension, showing my new design;

FIG. 2 is a rear perspective view thereof;

FIG. 3 is a left side perspective view thereof;

FIG. 4 is a right side perspective view thereof;

FIG. 5 is a top view thereof; and,

FIG. 6 is a bottom view thereof.

The broken lines and the grayed areas in the photographs depicting the base of the artificial lash extension are for illustrative purposes only and form no part of the claimed design.
